(57) **CLAIM**

The ornamental design for a wheel assembly, as shown and described.

DESCRIPTION

FIG. 1 is an exploded perspective view of a wheel assembly, showing my new design;

FIG. 2 is a front view of the wheel assembly;

FIG. 3 is a front view of the wheel assembly of FIG. 1 with a bolt cover ring and clamping units removed;

FIG. 4 is a side view thereof;

FIG. 5 is a rear view thereof;

FIG. 6 is a front view of a portion of the wheel assembly of FIG. 1, namely the bolt cover ring;

FIG. 7 is a rear view of the portion of the wheel assembly of FIG. 6;

FIG. 8 is a perspective rear view of the portion of the wheel assembly of FIG. 6; and,

FIG. 9 is a front perspective view of the inner wheel portion of the wheel assembly of FIG. 1.
